UNITED STATES PATENT OFFICE.

JOSEPH GALAMB, OF DETROIT, MICHIGAN, ASSIGNOR TO FORD MOTOR COMPANY, OF HIGHLAND PARK, MICHIGAN, A CORPORATION OF DELAWARE.

VIBRATOR ASSEMBLY FOR ELECTRICAL CIRCUITS.

Application filed January 3, 1921. Serial No. 434,630.

To all whom it may concern:

Be it known that I, JOSEPH GALAMB, a citizen of the United States, residing in the city of Detroit, county of Wayne, and State of Michigan, have invented new and useful Improvements in a Vibrator Assembly for Electrical Circuits, of which the following is a specification.

The object of my invention is to provide an improved vibrator assembly for electrical circuits of simple, durable, and inexpensive construction.

In connection with the use of vibrators for electrical circuits, and more especially in connection with the use of such vibrators with the coil assemblies used in the ignition systems of internal combustion engines, it has been found difficult to properly insulate supports for the contact members in a convenient and readily made form of device, and it has also been difficult to so construct these devices that they may be readily assembled upon the coil boxes used in connection with the coils of the internal combustion engines, as the supports for the contacts are usually secured to the coil box independently of each other.

With the foregoing explanation in mind, it is a further object of my invention to provide novel means for insulating the two contact points of the vibrator assembly from each other and to provide in combination with such insulating members, novel and convenient means for fastening the vibrator assembly together and to the coil box, these latter means also forming the members for completing the electrical circuits through the vibrator members.

A further object of my invention is to provide a unit type vibrator structure which may be adjusted when it is manufactured and simply fastened to the coil box without further adjustment.

A further object of my invention is to provide a unit type of vibrator structure as distinguished from a type of vibrator structure which must be assembled a piece at a time upon a coil box or other base.

A further object of my invention is to provide a vibrator assembly which may utilize the means by which it is attached to its support to form the electrical connections for the circuits therethrough.

With these and other objects in view, my

invention consists in the arrangement, combination and construction of the various parts of my improved device, as described in the specification, claimed in my claims, and shown in the accompanying drawings, in which:

Figure 1 is a side elevation of a coil box for an ignition circuit having my improved vibrator assembly mounted thereon,

Figure 2 is a top or plan view thereof,
Figure 3 is an end elevation of the vibrator assembly,

Figure 4 is a top or plan view of one of the pieces forming my vibrator assembly, and

Figures 5 and 6 are enlarged detail sectional views illustrating the manner of electrically insulating my improved assembly.

Referring to the accompanying drawings, I have used the reference numeral 10 to indicate, generally, a coil box for containing electrical coils which have a core member 11 extending from the top of the box. Threaded rods or bolts 12 and 13 extend upwardly from the coil box and are electrically connected with the coils therein so that when a circuit is closed between the rods 12 and 13, the circuit will be closed through the primary circuit of the coil within the box. Mounted on the bolts or rods 12 and 13 is a base member for my vibrator assembly, 85 which is illustrated in detail in Figure 4. This base member has ears 14 and 15 which have openings 16 and 17 therein designed to receive the rods 12 and 13 respectively. The sides of these ears 14 and 15 are bent downwardly somewhat to form the feet 18. Extending rearwardly from the base member between the ears 14 and 15 is a reed supporting lug 19 having a pair of threaded openings 20 and 21 therein.

Mounted on this base member is a reed member 22, which extends forwardly from the lugs 19 to position above the core 11, at which place it is enlarged to form an armature for the core 11. The rear end of the reed is perforated to receive screws 23 and 24, respectively, which enter the threaded openings 20 and 21 in the lug 19. Rivets may be used instead of the screws, if desired. It will be noted that the feet 18 are bent down from the ears 14 and 15, so that the lug 19 is supported in position spaced somewhat above the top of the

coil box 10 so that the tension on the reed may be varied by bending the lug 19 toward or away from the top of the coil box 10.

Above the base member of my assembly 6 is a bridge member which is provided with ears 25 and 26, which have openings therein to receive rods 12 and 13. The bridge member is bowed upwardly intermediate of the ears 25 and 26 and has a forward extension 10 27 which extends to position above the free end of the reed 22 and the core 11. Beneath the forward extension 27 on the bridge member is a cushion spring 28 which carries contact member 29. This cushion spring 28 is arranged to throw away from the extension 27 15 slightly and the throw is limited by a lug 30, which extends through the cushion spring and is fastened in the extension 27. A contact member 31 is secured to the top 20 of the free end of the vibrator or reed 22 in position to co-act with the contact member 29. A knob 35 may be secured to the bridge member for convenience in handling the same, if desired.

25 It will be noted that the ears 25 and 26 of the bridge member and the ears 14 and 15 of the base member each have openings therein designed to receive the bolts 12 and 13 respectively. These bolts or rods 30 are electrically connected with the terminals of the coils in the coil box so that when a circuit is closed therebetween then that a circuit will be closed through the proper coil. For causing the closing of this 35 circuit to be completed through the contacts 29 and 31 when the latter are brought together, I electrically insulate the rod 12 from the ear 14 and consequently from the base member; and the ear 26 from the rod 13, thereby insulating the bridge member 40 from the latter rod. As the contact 29 is carried by the bridge member and the contact 31 is carried by the reed, which in turn is connected with the base, it will be seen that bringing these contacts together 45 will complete the electrical circuit between the rods 12 and 13. The contacts 29 and 31 are so brought together normally by the resiliency of the reed 22, which throws said 50 contacts together thereby making the contact normally complete. When, however, the contact is completed the circuit is completed through one of the coils in the coil box, thereby energizing the coil and core 55 11 to draw the reed away from the bridge member, which in turn separates the contacts 29 and 31. The separation and closing of these contacts continues indefinitely in the manner well known in vibrators as 60 long as electrical current is supplied to the coils. If it is desired to adjust the torque or bend of the reed 22, this may be accomplished by bending the lug 19 toward the top of the coil box or away from it.

65 The installation and assembly of the

bridge and base members is accomplished as follows. In connection with the rod 13 insulating washers 36 separate the ear 26 from the ear 15 and insulate said members from each other. The washers are, however, held together, held in position to properly support the ear 26, and held against the ear 15 by a sleeve 32 which has its end bent out and turned over the washers 31 and ear 15 respectively. As this sleeve 70 32 contacts direct with the bolt 13 and with the ear 15 it will be seen that an electrical connection may be completed from the bolt 13 to the ear 15 and consequently to the base member. The rod 12 and the 75 sleeve 32 surrounding that rod are insulated from the ear 14 and the base member by the washers 33 and these parts are held together by the turning over the sleeve 32 in the manner illustrated in Figures 5 and 80 85 6. In this case it will be noted that the ear 25 of the bridge member contacts directly with the sleeve 32 thereby completing the circuit through the rod 12 to said bridge member.

90 From the foregoing description it will be seen that the base, bridge, reed and insulating washers may be assembled into a unitary structure and the lug 19 bent to give the reed 22 the proper tension before the device 95 is assembled on the coil box. When it is to be assembled the sleeves 32 are simply dropped down over the rods 12 and 13 and nuts 34 are tightened down to hold the vibrator structure in place.

100 From the foregoing description it will also be seen that I have provided a unitary structure which may be readily attached to a coil box and which utilizes the attaching means for completing the electrical circuits.

105 This vibrator structure is especially adapted for replacements, as a person without any experience may replace the vibrator structure on an old coil by simply unscrewing the nuts to remove the old vibrator, slipping the new vibrator on over the bolts 110 12 and 13, and then tightening down the nuts.

115 Some changes may be made in the arrangement and construction of the various parts of my improved device without departing from the spirit of the invention therein, and it is my intention to cover by my claims such changes as may be reasonably included within the scope thereof.

120 I claim as my invention:

1. In a device of the character described, a support, a base member having an arched portion, a bridge member secured to the base and insulated therefrom, said bridge having an arched portion, a reed mounted on the arched portion of the base, and contact devices mounted on portions of the bridge whereby the bridge and base may be primarily formed and assembled together to 125 130

properly position the reed and contact devices relative to the support and the final adjustment after the assembly has been secured to the support, by slight flexing of the 5 bridge and base members to the necessary positions.

2. In a vibrator assembly a base member having laterally projecting ears, feet members formed at either side of said ears and 10 bent downwardly therefrom to support the central portion of said ears in position above the support upon which said base member may be mounted, and a reed supporting lug extending from between said ears whereby 15 said lug may be bent toward or away from a support to adjust the tension on the reed.

3. In a vibrator assembly adapted to be secured as a unit structure upon a coil box, a base member having a body portion, laterally extending ears at either side thereof, offset foot members extending from said ears, and a reed supporting lug extending from 20 said body member, and a bridge member having ears adapted to be secured to but insulated from said ears on the base member,

a cushion spring mounted on said bridge member, a contact mounted on said cushion spring, a reed mounted on the reed supporting extension, a contact mounted on said reed, and a handle member secured to said 30 bridge member.

4. In a device of the class described, a support, spaced rods extending therefrom, a base member having ears with openings therein to receive said rods, said base member having rearward extensions therefrom, a bridge member having ears with openings therein to receive said rods, said bridge member having a forward extension, a contact secured to said forward extension, and 35 a reed member mounted on the rearward extension of the base and extending to position below the end of said forward extension on the bridge, and a contact on said reed in position to co-act with the contact on said 40 bridge member.

JOSEPH GALAMB.
